Primary Examiner — Robert M Spear*Assistant Examiner* — Ryan Harvey(74) *Attorney, Agent, or Firm* — Jansson Munger McKinley and Shape Ltd.(57) **CLAIM**

The ornamental design of a front bumper cover for a car, as shown and described.

DESCRIPTION

FIG. 1 is a perspective view of the front bumper cover for a car of the present design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof. The broken lines illustrate portions of the article that form no part of the claimed design.
